UNITED STATES PATENT OFFICE.

CHARLES H. BOECK, OF JACKSON, MICHIGAN, ASSIGNOR TO NOVELTY MANUFACTURING COMPANY, OF JACKSON, MICHIGAN, A CORPORATION OF MICHIGAN.

DESIGN FOR A FOOT-WARMER.

SPECIFICATION forming part of Design No. 37,194, dated October 25, 1904.

Application filed September 3, 1904. Serial No. 223,292. Term of patent 14 years.

To all whom it may concern:

Be it known that I, CHARLES H. BOECK, a citizen of the United States, residing at Jackson, in the county of Jackson and State of Michigan, have invented and produced a new, original, and ornamental Design for Foot-Warmers, of which the following is a specification, reference being had to the accompanying drawing, forming a part thereof.

5 The figure is a perspective view of a foot-warmer, showing my new design.

I claim as new and desire to secure by Letters Patent of the United States—

The ornamental design for a foot-warmer, substantially as shown.

CHARLES H. BOECK.
